UNITED STATES PATENT OFFICE

159,361

DUPLEX HAIRBRUSH

Ferdinand Nussbaum, Forest Hills, N. Y.

Application May 6, 1948, Serial No. 146,199

Term of patent 7 years

(CL. D86—10)

To all whom it may concern:

Be it known that I, Ferdinand Nussbaum, a citizen of the United States, residing at Forest Hills, L. I., in the county of Queens and State of New York, have invented a new, original, and ornamental Design for a Duplex Hair Brush, of which the following is a specification, reference being had to the accompanying drawing, forming part thereof, in which—

Figure 1 is a top plan view of the duplex hair brush, showing my new design;

Fig. 2 is a side view;

Fig. 3 is a rear plan view; and

Fig. 4 is a front view.

It is understood that the bristles and teethlike projections shown in quarter section are to extend over the central oval area.

I claim:

The ornamental design for a duplex hair brush, as shown and described.

FERDINAND NUSSBAUM.
